UNITED STATES PATENT OFFICE.

RALPH BROWNSON, OF HASTINGS, MINNESOTA.

BAG.

Application filed December 10, 1923. Serial No. 679,611.

To all whom it may concern:

Be it known that I, RALPH BROWNSON, a citizen of the United States, residing at Hastings, in the county of Dakota and State of Minnesota, have invented certain new and useful Improvements in Bags, of which the following is a specification.

The present invention relates to bags, and more particularly to an improved carrying bag for containing and transporting merchandise.

In bags for transporting merchandise wherein a cord is used as a carrying means, difficulty has been experienced in making a bag which would support the weight of the bag and contents by either handle, and which would not permit the walls of the bag to sag down and fold against the cord.

An object of the present invention is to improve and strengthen a bag having a cord as a carrying means.

A further object is to prevent slippage of the carrying cord while maintaining the strength of the bag and associated parts.

In order to attain these objects, there is provided, in accordance with one embodiment of this invention, a bag having a plurality of carrying cords arranged to provide double strands thereof at the top of the bag to form handles, and single strands thereof around the bottom of the bag to support the bag and contents.

These and other features of the invention not specifically mentioned will be apparent from the following description and the accompanying drawings, wherein:

Figure 1, is a view in perspective of a carrying bag embodying one form of the invention.

Figure 2, is a view, also in perspective, of the cords thereof; and

Figure 3, is a partial detail view.

Referring to the drawings in detail, 10 represents a bag which may be of paper.

The upper portion 11 of the bag is folded as illustrated, and between this folded portion and the walls of the bag itself are inserted support members 12, which may be of cardboard.

In the form illustrated, cords 13 and 14, which are preferably of twisted paper, are placed in parallel loops around the bottom of the bag, run through the apertures 15 and 16, respectively, into the interior of the bag, up the side walls thereof, and out again through the apertures 17 and 18, said

apertures being formed in the bag below the support members 12. The end of each of the projecting portions is looped over to a point adjacent that at which the other projecting cord on the same side of the bag emerges from the interior of the bag. This forms a handle of double strand, the looped portions thereof being coextensive. The staples 19 embrace both cords on the outside of the bag and the upturned end of the cord which terminates at that point, on the inside of the bag.

The end of each terminating cord on each side of the bag is looped around the supports 12, as best illustrated in Figure 2, and anchored by the wire staples 19, passing through the support members 12 and around the cords on opposite sides of said members.

The single strand of cord passing down the sides and around the bottom of the bag is amply strong to support, with the aid of the material of which the bag is constructed, a considerable weight of merchandise; and the carrying handles, being 75 of double strand, strengthen a hitherto weak point in bags of this type.

It is apparent, that in using a bag of this type it is sometimes desirable to hold the bag by one handle and place merchandise 85 therein. This naturally exerts a considerable strain on this handle and the side of the bag on which it is located. A bag constructed in accordance with applicant's invention, however, will easily support a considerable weight of merchandise in this manner.

An important feature of the invention is the method of anchoring the handles to the top of the bag. By passing the cord 95 through openings underneath the supports 12, and anchoring the cord upon both sides of the supports by staples which pass through the supports and embrace the cords upon opposite sides, a particularly strong 100 handle support is secured.

I am aware that it is old to fasten handles to members arranged between the folded portion at the top of the bag by stapling the handles directly to such members, but 105 there is not in such constructions the strength and other advantages secured in my construction, wherein the cords are looped around the members 12 and anchored upon opposite sides thereof; and I am also aware 110 that it is old to provide a bag with carrying cords looped around the same, as, for

instance, where cords slidably extend around the bottom of a bag, but in such constructions there is not the bracing of the bag and the sustaining of the load by a lift upon one handle, and other advantages that exist in the construction shown in the drawings herein.

What I claim is:

1. In combination with a bag, bracing means connected to the upper portion of the bag, parallel cords extending through openings in the walls of the bag and around the bottom thereof, handles formed by looping the upper portion of the cords on each side 10 of the bag in opposite directions to be co-extensive, a bent portion in each end of each cord supported by the bracing means, and means for fastening the cords to the bracing member and to the bag at each point of 15 crossing of the bracing member by the cords.
2. In combination with a bag, a folded portion at the top of the bag, bracing members between such folded portion and the walls of the bag, a plurality of cords looped 20 under the bottom of the bag and up the sides thereof, openings in the walls of the bag through which the cords pass into the interior thereof, other openings adjacent the bracing members through which the cords 25 emerge from the bag, double strand handle loops formed by placing each projecting

cord end in proximity to the point at which the other cord on the same side of the bag emerges from the bag, and means for securing the cords to the bag and to the bracing 35 member.

3. In combination with a bag of the class described, having a folded upper edge, strip supporting members enclosed within said folded upper edge, cords extending around the bottom of the bag and upwardly beyond the side walls of the bag in looped form to form handles, the ends of said cords being looped around said strip supporting members, and fastening means extending through 40 said supporting members and embracing the cords upon opposite sides of said members.

4. In combination with a bag, a pair of cords looped around the bottom of the bag and up the sides thereof to extend above the top 45 of the bag, each extending portion of each cord being looped over to a point adjacent that at which the other cord on the same side of the bag extends above the top of the bag, said looped portions on each side 50 of the bag being coextensive, and fastening means to secure an end of one strand to an intermediate portion of another strand and to the bag.

In testimony whereof I affix my signature.

RALPH BROWNSON.
